COMBINED STORAGE AND DISPLAY RACK FOR SHOES OR THE LIKE

William E. Mitchell, 162 W. 5th St., New York, N.Y.

Filed Oct. 25, 1962, Ser. No. 72,257

Term of patent 3½ years

(Cl. D80—10)

2176.1

FIG. 1 is a side front perspective view of the combined storage and display rack for shoes or the like showing my new design.

FIG. 2 is a rear elevational view thereof.

FIG. 3 is a top plan view thereof, one corner being broken away for convenience of illustration.

I claim:

The ornamental design for a combined storage and display rack for shoes or the like, substantially as shown.
